Primary Examiner — Elizabeth J Oswecki(74) *Attorney, Agent, or Firm* — Che-Yang Chen; Law Office of Michael Chen(57) **CLAIM**

The ornamental design for a storage cabinet, as shown and described.

DESCRIPTION

FIG. 1 is a perspective view of a storage cabinet showing my new design;

FIG. 2 is a rear elevational view thereof;

FIG. 3 is a front elevational view thereof;

FIG. 4 is a left side elevational view thereof;

FIG. 5 is a right side elevational view thereof;

FIG. 6 is a top plan view thereof;

FIG. 7 is a bottom plan view thereof; and,

FIG. 8 is an enlarged portion view taken from encircled portion labeled, "FIG. 8," in FIG. 1.

The even broken lines shown in the drawings represent portions of the storage cabinet that form no part of the claimed design. The dashed-dot lines represent the boundary of the enlarged portion view of FIG. 8 shown in FIGS. 1 and 8 that forms no part of the claimed design.
